US00D638406S

(12) United States Design Patent
Chiang

(10) Patent No.: US D638,406 S
(45) Date of Patent: * May 24, 2011

(54) SUPPORT FOR ELECTRONIC DEVICE

(75) Inventor: Ching-Liang Chiang, Taoyuan County (TW)

(73) Assignee: HTC Corporation, Taoyuan (TW)

() Term: 14 Years

(21) Appl. No.: 29/359,119

(22) Filed: Apr. 6, 2010

(51) LOC (9) Cl. 14-01

(52) U.S. Cl. D14/224

(58) Field of Classification Search D14/205, D14/206, 223, 224, 227, 229, 238, 230, 251, D14/253, 432, 434, 451, 452, 496, 217, 224.1; D13/107, 108; 320/115; 248/278.1, 274.1; 379/420.02, 420.04, 430, 420.01, 420.03, 379/433.01, 433.03

See application file for complete search history.

(57) CLAIM

The ornamental design for support for electronic device, as shown and described.

DESCRIPTION

FIG. 1 is a front perspective view thereof;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
